REGINALD F. HERSEY, OF BEVERLY, MASSACHUSETTS.

HAND-VISE.

1,162,053.

Specification of Letters Patent. Patented Nov. 30, 1915.

Application filed April 1, 1915. Serial No. 18,566.

To all whom it may concern:

Be it known that I, REGINALD F. HERSEY, a citizen of the United States, residing at Beverly, in the county of Essex and State of Massachusetts, have invented certain new and useful Improvements in Hand-Vises, of which the following is a specification.

This invention contemplates an improved hand vise or tool especially adapted for use in manually holding an object with one hand while the other hand may be employed in operating upon the said object.

The invention has as its primary object to provide a tool of this character adapted to be locked in engagement with the work and which may be readily operated to either engage or free the work.

A further object of the invention is to provide a tool of this character having co-acting arms simultaneously adjustable to adapt the tool for use in connection with various sizes of work, and wherein the said arms will be provided with swingingly mounted jaws adapted to thus seat flatly upon opposite sides of the work in secure engagement therewith.

The invention has as a still further object in this connection, to provide means for limiting the swinging movement of the jaws in each direction; to provide yieldable means normally urging the jaws to the limit of their pivotal movement in one direction, and to provide means for simultaneously moving the arms carrying the jaws, for urging the jaws into engagement with the work.

The invention has as a still further object to provide yieldable means connected to said arms for normally urging the inner ends of the arms toward each other and consequently normally holding the jaws mounted upon the outer ends of the said arms in spaced relation to receive the work. And a still further object of the invention is to provide a tool which will be simple in construction, which may be easily manipulated, and which will be found thoroughly efficient in use.

Other and incidental objects will appear as the description proceeds and in the drawings wherein I have illustrated the preferred embodiment of the invention and wherein similar reference characters designate corresponding parts throughout the several views, Figure 1 is a side elevation of my

improved tool, Fig. 2 is a horizontal sectional view of the device more particularly illustrating the detail construction thereof, Fig. 3 is a transverse sectional view taken on the line 3—3 of Fig. 2 and looking in the direction of the arrows. Fig. 4 is a plan view more particularly showing the construction and mounting of the jaws of the device.

Referring more particularly to the drawings, my improved tool includes a shank 10 which at one extremity, is longitudinally bored as shown at 11 and which is medially enlarged to provide an annular body portion 12. Surrounding the bored extremity 11 is a preferably wooden handle 13 which, at one end is adapted to abut the body portion 12 and is preferably provided with a ferrule 14, it being observed that the adjacent end of the shank is overturned for connecting the handle therewith.

The shank 10 at its free end, is bifurcated to form spaced ears 15 having alined openings formed therein in which is freely mounted a pin 16 having right and left hand screw threads formed on the respective extremities thereof. Keyed upon the pin 16 and freely received between the ears 15, is an annular nut 17, the periphery of which is preferably knurled as best shown in Fig. 1 of the drawings. It will thus be observed that the pin 16 may be readily rotated through the medium of the nut 17.

Mounted upon the pin 16 are coacting arms 18, each of which intermediate its ends, is enlarged to provide a body portion 19. The body portion 19 of each of said arms is provided with a transversely extending opening 20 which enters through opposite edges thereof and is further provided with a cylindrical opening intersecting the opening 20 and disposed at substantially right angles thereto, the said last mentioned opening entering through opposite side faces of the body portion and freely receiving a substantially cylindrical pivot pin 21 to turn therein.

It will be observed that the body portion 19 of each of said arms is preferably provided with flat side faces and that the ends of each of said pivot pins terminates substantially flush with the side faces of the body portion by which it is supported. The pivot pins 21 are provided with internally screw threaded bores to respectively

receive the right and left hand threads of the pin 16, which, as best shown in Fig. 2 of the drawings, is arranged to project at its free extremities freely through the openings 20 of the body portions 19. The arms 18 are thus pivotally connected with the shank 10 and are simultaneously adjustable either toward or away from each other through the medium of the pin 16.

10 The arms 18, at their free extremities, are bifurcated to form spaced lugs or extensions 22 which extend from the body portions 19 of the said arms in oblique relation thereto, the extensions of one arm projecting laterally toward the extensions of the other arm. The extensions 22 of each arm adjacent the outer terminals thereof are provided with alined openings receiving a pivot pin 23 upon which is pivotally mounted a jaw 24, 15 freely received between the said extensions, the jaw of one arm being adapted to coact with the jaw of the other arm.

Each of the jaws 24 is provided with a laterally extending head 25 as best shown 20 in Fig. 4 of the drawings, which is formed with a substantially flat knurled working face adapted to engage the work in the manner shown in Fig. 1 of the drawings, the work being conventionally illustrated therein. The heads 25 of the jaws upon the inner sides thereof, are arcuately cut away to freely receive the rounded terminals of the extensions 22 and to provide at their outer extremities, laterally projecting shoulders 26 extending upon opposite sides of the said extensions and adapted to contact with the adjacent inner edges thereof for limiting the jaws in their pivotal movement in one direction upon the pins 23. The said jaws 30 are each provided with a tail 27 which project between the extensions 22 toward the body portions 19 in the manner best shown in Fig. 2 of the drawings, the said tails being integrally formed on the heads 25 and 35 extending laterally therefrom. At their outer free ends, the tails 27 are beveled to seat flatly against the flat faces or shoulders 28 formed on the said body portions 19. As will be clear, the tails 27 of the said jaws are 40 thus adapted to limit the jaws in their pivotal movement in a reverse direction to that defined by the shoulders 26.

The body portion 19 of each of the arms 18 is provided with a substantially cylindrical socket 29, while the head 25 of each 50 of the jaws 24 at a point substantially midway of its ends, is provided with a similar socket 30. Seating at its ends in respective corresponding sockets 29 and 30 is a substantially helical spring 31 of the expansive type. The springs 31 are disposed substantially midway between the extensions 22 and normally urge the jaws 24 to the limit of their outward pivotal movement with the 55 tails 27 thereof in engagement with the

shoulders 28. The purpose in the particular mounting of the jaws 24 thus described, will be presently referred to.

The inner extremities of the arms 18 are curved laterally toward each other and at 70 the inner ends thereof, are reduced being each provided with a terminal foot 32 having an inner arcuate face or shoulder 33 formed thereon. As best shown in Fig. 2 of the drawings, the body portion 12 of the 75 shank is formed with a transversely extending recess 34 which opens through opposite sides thereof and in which the inner terminals of the arms 18 are freely received.

It will be observed upon reference to Fig. 80 2 that the bore 11 of the handle at its inner extremity terminates in a reduced bore 35, which at one end communicates with a bore 36 extending transversely through the shank 10. Freely mounted within the bore 11 of 85 the shank is a wedge 37 in the nature of a rod which adjacent one end thereof, is cut away upon opposite sides to provide transversely extending notches 38. The adjacent extremity of the rod 37 is flattened and is 90 provided with a wedge shaped terminal 39 having oppositely inclined shoulders 40 adapted to be projected between the inner extremities of the arms 18 to engage the curved faces 33 of the feet 32 of the said 95 arms. At the contiguous extremity thereof, the rod 37 is reduced to provide a pin 41 adapted to be freely received within the bore 35, the said pin being disposed to engage within the said bore for guiding and supporting the adjacent terminal of the rod 37. 100

Formed upon one side of the body portion 12 of the shank are spaced laterally projecting ears 42 between which is pivotally mounted an operating lever 43, the said lever 105 being preferably detachably connected with the ears by a suitable pivot pin 44.

The lever 43 is of a length substantially equal to the length of the handle 13 and adjacent the outer extremity thereof is transversely curved to seat against the said handle. Integrally formed on the lever at the inner extremity thereof, are spaced laterally projecting arms 45 arranged to freely embrace the adjacent portion of the rod 37 115 to engage within the notches 38. The arms 45 are each of substantially spatulate form, to thus present upon opposite edges thereof, cam faces 46 adapted to engage opposite end walls of each of said notches for moving the 120 rod 37 longitudinally within the shank 10.

Mounted upon the arms 18, adjacent to the inner extremities thereof, are oppositely disposed pins 47 which are arranged in alignment with the bore 36 formed in the shank 125 10 and which at their inner extremities are provided with eyes engaging the terminals of a helical spring 48 which extends freely through the said bore, the said spring normally urging the inner ends of the arms to- 130

ward each other and being adapted to normally maintain the feet 32 of the said arms in engagement with the wedge shaped terminal 39 of the rod 37.

5 From the preceding description, it is thought that the operation of my improved tool will be readily understood. It will be noted as previously set forth, that by manually turning the disk 17 to consequently rotate the rod 16, the pivot pins 21 of the arms 18 may be simultaneously adjusted either toward or away from each other. The jaws 24 will consequently be similarly adjusted to receive the work and in this connection, 15 particular attention is directed to the fact that owing to the pivotal mounting of the said jaws, the jaws will, upon being brought into contact with the work, move into such angular relation to the extensions 22 of the 20 arms 18 supporting the jaws, as to bear flatly against the work in the manner shown in Fig. 1 of the drawings, even though the work be relatively thick or relatively thin. However, it is to be observed that the jaws 25 are positively limited in their pivotal movement upon the extensions 22 in each direction and are normally urged in one of said directions away from each other by the springs 31, to receive the work.

30 In use, the lever 32 is swung upon its pivot 44 laterally away from the handle 13. Such movement of the lever will cause the arms 45 to engage within the notches 38 of the rod 37 and consequently move the rod longitudinally within the bore 11 of the handle toward the outer end thereof. The wedge shaped terminal 39 will, as a consequence, be moved out of engagement with the feet 32 of the arms 18 when the spring 48 will 40 move the inner ends of said arms toward each other causing the arms to pivot upon the pins 21 and consequently move the jaws 24 away from each other. The work is then inserted between the jaws and the lever 43 45 is moved toward the handle to the position shown in Fig. 2 of the drawings. It will be noted that when the handle is so moved, the cam faces 46 of the arms 45 of the handle will engage the inner end walls of the 50 notches 38 to move the wedge shaped terminal 39 of the rod 37 longitudinally between the feet 32 of the arms 18. The inclined walls 40 of the said wedge shaped terminals will thus engage the arcuate faces 55 33 of the said feet to force the inner terminals of the arms 18 away from each other and consequently move the jaws 24 into binding engagement with the work. It is further desired to direct particular attention 60 to the fact that the cam faces 46 of the arms 45 are so disposed relative to the pivot pin 44 of the operating lever 43, that when the said lever is thus moved to cause the jaws 24 to engage the work, the lever 43 is adapted 65 to assume a position upon one side of a piv-

otal center, with the wedge shaped terminal 39 consequently locked between the inner ends of the arms 18.

It will thus be seen that I provide a very simple and efficient tool for the purpose set forth which may be readily operated by one hand to hold the work, while the work may be manipulated with the other hand. It will further be seen that since, after the jaws 24 are engaged with the work, the operating lever 43 will be urged to the normal position particularly shown in Fig. 2 of the drawings, that the tool will not be liable to become disengaged from the work and thus will provide a very efficient tool in practical use.

Having thus described the invention, what I claim and desire to secure by Letters Patent is:—

1. A device of the character described including a shank having spaced ears formed on the free extremity thereof, a pin rotatably mounted upon said ears, a thumb nut keyed upon the pin and freely disposed between said ears, arms formed to freely receive the pin and pivotally supported thereby, the said arms being simultaneously adjustable upon the pin either toward or away from each other, coacting jaws carried by the outer extremities of said arms, a wedge mounted upon the shank and adapted for movement to engage between the inner extremities of the arms for urging the outer extremities thereof toward each other, and an operating lever for the wedge.

2. A device of the character described including a solid shank hollow at one extremity, coacting arms pivotally mounted upon the shank, coacting jaws carried by the outer extremities of said arms, a wedge slidably mounted in the hollow extremity of the shank and adapted for movement therein to engage between the inner extremities of the arms for urging the outer extremities thereof toward each other, and an operating lever pivotally mounted upon the shank and freely embracing said wedge to slidably engage therewith for actuating the wedge.

3. A device of the character described including a shank provided with a longitudinally extending bore, coacting arms pivotally mounted upon the shank, coacting jaws carried by the outer extremities of said arms, a wedge shiftably mounted within said bore and adapted for movement therein to engage between the inner extremities of the arms for urging the outer extremities thereof toward each other, the wedge being cut away upon opposite sides, and an operating lever mounted upon the shank and provided with spaced arms slidably engaging in the cut away portions of the wedge for actuating the said wedge.

4. A device of the character described including a shank provided with a longitudi-

nally extending bore and having an opening formed therein communicating with said bore, coacting arms pivotally mounted upon the shank, coacting jaws carried by the outer 5 extremities of said arms, the inner extremities of said arms extending within said opening, means normally urging the inner ends of the arms toward each other, a wedge shiftably mounted in said bore and adapted 10 for movement therein to project into said opening in engagement between the inner extremities of said arms for urging the outer extremities thereof toward each other, and an operating lever pivotally mounted upon 15 the shank and having arms formed thereon freely embracing the wedge for actuating the said wedge.

5. A device of the character described including a shank, coacting arms pivotally mounted upon the shank, coacting jaws pivotally mounted upon the outer extremities of said arms, means for limiting the jaws in their pivotal movement in each direction, yieldable means normally urging the jaws 20 to the limit of their pivotal movement away from each other, yieldable means normally urging the inner extremities of said arms toward each other, a wedge shiftably mounted upon the shank and adapted for movement 25 thereon to engage between the inner extremities of the arms for urging the outer extremities thereof toward each other against the tension of said last mentioned means, and an actuating lever pivotally mounted upon the shank and freely engaging 30 the wedge.

6. A device of the character described including a shank, coacting arms swingingly mounted upon the shank, coacting jaws pivotally mounted upon said arms, means limiting the jaws in their pivotal movement in each direction, yieldable means urging the jaws to the limit of their movement in one direction away from each other and means 40 for moving the said arms to urge the said jaws toward each other.

Copies of this patent may be obtained for five cents each, by addressing the "Commissioner of Patents, Washington, D. C."

7. A device of the character described including a shank, coacting arms pivotally mounted thereon and provided with extensions, coacting jaws pivotally mounted between said extensions and provided with lugs adapted to engage the arms for limiting the jaws in their movement away from each other, yieldable means engaging the jaws for urging the lugs thereof into engagement with the arms, and means for moving the arms to urge the jaws toward each other. 50 55

8. A device of the character described including a shank, coacting arms swingingly mounted thereon and provided with extensions having curved ends, coacting jaws swingingly mounted upon said extensions and provided with recesses freely receiving the curved ends of the extensions and forming shoulders adapted to engage the extensions for limiting the jaws in their swinging movement upon the extensions toward each other, lugs carried by the jaws and adapted to engage the arms for limiting the jaws in their swinging movement away from each other, and means for moving the arms to urge the jaws toward each other. 60 65 70

9. A device of the character described including a shank formed to receive a wedge, coacting arms swingingly mounted upon the shank, coacting jaws carried by said arms, a wedge mounted upon the shank and adapted to engage between the inner extremities of the arms for urging the jaws toward each other, and an operating lever pivotally mounted upon the shank and provided with spaced arms having cam faces adapted to slidably engage the wedge for moving the wedge into engagement with said arms. 75 80 85

In testimony whereof I affix my signature in presence of two witnesses.
